UNITED STATES PATENT OFFICE.

NICKOLAS F. EGLER, OF CHICAGO, ILLINOIS.

HEATING-FURNACE.

1,380,095.

Specification of Letters Patent. Patented May 31, 1921.

Application filed August 29, 1919. Serial No. 320,602.

To all whom it may concern:

Be it known that I, NICKOLAS F. EGLER, a citizen of the United States, residing at Chicago, in the county of Cook and State 5 of Illinois, have invented a new and useful Improvement in Heating-Furnaces, of which the following is a full, clear, and exact description, reference being had to the accompanying drawing, forming part of this specification, in which—

Figure 1 is a vertical longitudinal section through the chamber of a heating furnace embodying my invention.

Fig. 2 is a vertical section along the line 15 II—II of Fig. 1.

Fig. 3 is a horizontal section through one of the baffles, and

Fig. 4 is a similar horizontal section showing a modification.

20 The present invention relates to heating furnaces, and more particularly to heating furnaces having elongated chambers into one end of which the gaseous fuel is introduced and burned, and from the other end of which the waste products of combustion escape. In this type of furnace, particularly when used as a continuous furnace for heating billets or the like, the billets or workpieces are pushed through the furnace along skid pipes which are near the bottom of the furnace. The hot gases of combustion tend to hug the roof of the furnace rather than go to the bottom of the furnace where the workpieces are. The result is that the furnaces 30 are uneconomically operated and more fuel is burned than would be necessary if the current of gases were caused to flow along the bottom of the furnace where the work to be heated is.

40 To overcome this difficulty I have provided a baffle or baffles in the top of the furnace chamber which keep the current of gases from hugging the top of the furnace chamber, and deflect it downward to the bottom of the furnace chamber where the workpieces are.

In the drawing, the invention is illustrated as embodied in a continuous heating furnace of well-known type in which the workpieces 50 or billets travel through the furnace chamber on skid pipes. Referring to the drawing, the furnace is indicated generally by reference numeral 2, and has the usual elongated furnace chamber 3. Extending longi-

tudinally of the furnace are the usual water-cooled skid pipes 4 which are spaced from the bottom of the furnace, being mounted on supports 5, as illustrated. The workpieces, shown as billets 6, are supported on the skid pipes 4 and are pushed through the furnace in the usual way. The fuel, which is usually gas, is supplied through a port or ports 7 at one end of the furnace. The hot products of combustion travel along the furnace and out through a flue 8 to the stack. 65 The furnace, as above described, is well-known in this art, and further details of its structure are unnecessary.

In this type of furnace the products of combustion tend to run along the roof of the 70 furnace so that while the top of the furnace is maintained at an intense heat, the space at the bottom of the furnace beneath the workpieces is much cooler. In order to direct the current of hot gases from the top 75 of the furnace to the region along the bottom of the furnace where the heating is to be done, I provide a baffle or baffles across the top of the furnace chamber. In the drawings I have indicated two baffles 10. Each 80 baffle consists of an iron frame 11 filled with firebrick 12. As shown in the drawing, the frame 11 is water-cooled. Each baffle 10 depends through an opening through the roof of the furnace and is hung by a supporting cable 13 so as to be vertically adjustable. When small workpieces are to be heated, the baffles or dampers may be lowered and when larger workpieces are to be heated, the baffles may be correspondingly 85 raised. The baffle or baffles 10 serve to deflect the stream of the hot gases of combustion from the roof of the furnace and cause them to travel along the bottom of the furnace and under the work, so that the work is 90 heated with a much less consumption of fuel.

In Fig. 3 I have illustrated a cross section of one of the baffles in which the frame comprises round water pipes 15 for supporting the brick work, while in Fig. 4 I have shown 100 a modification in which square water pipes 16 with concave faces are used for supporting the brick work of the baffle. The brick work is preferred as the filler for the baffle frame, but other refractory material might 105 be used.

While, for the sake of illustration, I have shown the furnace as provided with two

baffles, it will be understood that the number of baffles may be varied to meet the furnace conditions.

While I have illustrated and described 5 the preferred embodiment of my invention, it is to be understood that the invention is not limited to its illustrated embodiment, but may be embodied in other furnace structures within the scope of the following 10 claims.

I claim:

1. A heating furnace having a chamber along which the hot gases of combustion travel, elevated tracks along which the 15 workpieces travel through the furnace chamber, and means for deflecting the stream of hot gases from the furnace roof toward the floor of the furnace and beneath the workpieces, substantially as described.
- 20 2. A heating furnace having an elongated horizontal chamber along which the hot gases of combustion travel longitudinally, and a plurality of baffles along the top of the furnace to prevent the stream of hot gases 25 from hugging the furnace roof, substantially as described.
- 25 3. A heating furnace having a chamber along which the hot gases of combustion

travel, and a vertically adjustable baffle or baffles across the top of the furnace chamber, 30 substantially as described.

4. A heating furnace having a chamber along which the hot products of combustion travel, tracks at the bottom of the furnace chamber along which the workpieces travel 35 through the furnace chamber, and a vertically adjustable baffle or baffles depending from the roof of the furnace, substantially as described.

5. A heating furnace having a chamber 40 along which the hot products of combustion travel, elevated tracks along which the workpieces travel through the furnace chamber, and a baffle or baffles at the top of the furnace chamber, substantially as described, 45

6. A heating furnace having a chamber along which the hot products of combustion travel, elevated tracks along which the workpieces travel through the furnace chamber, and a vertically adjustable baffle or 50 baffles at the top of the furnace chamber, substantially as described.

In testimony whereof, I have hereunto set my hand.

NICKOLAS F. EGLER.
